UNITED STATES PATENT OFFICE.

MARY A. HENRY, OF NEW CASTLE, PENNSYLVANIA.

DESIGN FOR A CURTAIN SHADE.

Application filed May 25, 1928. Serial No. 26,852. Term of patent 3½ years.

To all whom it may concern:

Be it known that I, MARY A. HENRY, a citizen of the United States, residing at New Castle, in the county of Lawrence and State of Pennsylvania, have invented a new, original, and ornamental Design for a Curtain Shade, of which the following is a specification, reference being had to the accompanying drawing, forming part thereof.

The figure is a plan view of a curtain shade, showing my new design.

I claim:

The ornamental design for a curtain shade, as shown.

MARY A. HENRY.
